UNITED STATES PATENT OFFICE.

FRANK CALABRESE, OF CHICAGO, ILLINOIS.

VENTILATOR.

Application filed April 16, 1923. Serial No. 632,253.

To all whom it may concern:

Be it known that I, FRANK CALABRESE, a subject of the King of Italy, and a resident of Chicago, in the county of Cook and State 5 of Illinois, have invented certain new and useful Improvements in Ventilators, of which the following is a specification.

My invention relates to ventilator mechanism which can be used for ventilating purposes in general, but which is particularly useful in homes for permitting the outflow of foul air and the inflow of fresh air without causing draft.

The usual type of ventilator requires for 15 its application or operation the opening of a window. The ventilators are usually applied at the sill at the opening afforded below the raised window sash. This however causes an opening between the upper and 20 lower sashes through which there will be unrestricted flow which will more or less upset ventilating current and cause drafts. The principal object of my invention is to provide ventilating mechanism which can be applied directly to the window panes in any position desired, making it unnecessary to open the windows and therefore making it possible to control ventilation as desired. In 25 carrying out my invention I cut a hole in the window pane at the desired location, and provide a suitable guide for sliding a shutter, preferably of glass, for opening or closing the opening to any degree desired, and preferably screening material is applied 30 over the opposite side of the pane opening.

My improved mechanism and its application and operation are illustrated on the accompanying drawing, in which—

Fig. 1 is an elevational view of a section 40 of window pane showing the ventilating apparatus applied thereto.

Fig. 2 is a sectional view on plane 2—2 Fig. 1.

The ventilating opening 5 is cut in the 45 window pane 6 and may be elliptical as shown, or of any other shape. The shutter 7 is preferably of glass and of the same general outline as the ventilating opening with which it is to be associated. As shown 50 the shutter is guided between the pane and a vertical bar 8 to be slid up and down against the window pane to open or close the ventilating opening 5 as desired. The bar is detachably secured at its upper and lower 55 ends by screws or bolts 9 and 10 which ex-

tend through holes 11 and 12 formed in the window pane. The shutter may be supported on either side of the pane but preferably on the outside thereof so as to better protect the ventilating opening against the entrance 60 of rain, snow, etc. To provide sufficient clearance for easy sliding of the shutter, washers 13 and 14 are interposed between the bar ends and the window pane, and the lower washer 14 is preferably of some soft 65 material such as rubber to serve as a cushioning abutment or seat for receiving the shutter when it is lowered away from the ventilating opening. The threaded ends of the bolts are received by nuts 15 between 70 which and the pane cushioning washers 16 are interposed to prevent strain on the glass when the nuts are tightened.

The bar 8 has the longitudinal slots 17 through which extends a bolt 18 which is inserted through the opening 19 provided at the upper edge of the shutter, the head of the bolts being preferably countersunk so as to leave the inner face of the shutter 75 smooth and free to slide along the pane. The shank of the bolt extends through the slot 17 and its reduced threaded end 20 receives a clip 21 which is held to the screw between the shoulder 22 and the nut 23 engaging the threaded end 20. At its upper 80 end the clip has a hole 24 for receiving the end of a cord 25, and this cord extends through a thimble 26 inserted in the opening 27 provided in the window pane above the 85 ventilating opening 5. This thimble may be 90 of sheet metal inserted through the opening 27 and having its ends riveted over against the sides of the window pane. The cord extends downwardly and through a suitable fitting (not shown) by means of which it 95 may be fastened to hold the shutter in any desired position with reference to the ventilating opening. There are many forms of 100 clamping pulleys and other devices on the market which can be readily used in connection with the cord and these can be fastened to the window frame or sill, or sash as desired. The slot 17 extends upwardly a distance beyond the thimble 26 so that the cord 105 may travel through the slot during adjustment of the shutter.

On the opposite side of the window pane a suitable screen 28 of wire or perforated metal is applied over the ventilating opening 5 and may be readily secured in place 110

by means of rivets or bolts 29 whose heads are countersunk so as not to interfere with the sliding movement of the shutter.

As the shutter is supported from its upper end above its center of gravity it will always hang and slide true, and by manipulating the cord the shutter can be raised and lowered to any position. The shutter supporting screw 18 traveling in the slot 17 will 5 guide the shutter in its vertical movement and the bar will keep the shutter against the window pane but will permit it to slide freely. The cushioning abutment 14 will prevent injury to the shutter should it be 10 too rapidly lowered. When the ventilating mechanism is applied to a sliding, swinging or other movable window the cord locking fitting (not shown) will be secured to the window sash, so that the window may be 15 moved as a whole without interfering with the adjustment of the ventilating mechanism.

I thus provide simple and efficient ventilating mechanism which will permit the 20 outflow of smoke, steam, or foul air from a room and the inflow of fresh air without causing drafts, and the mechanism can be applied and manipulated without interfering with the opening or closing of the window structure. I do not desire to be limited to the exact construction, arrangement 25 and operation shown and described as modifications can be made which will still come within the scope of the invention.

30 I claim as follows:

1. In ventilating mechanism, the combination of a window pane having a ventilating opening, a shutter for said opening in the form of a glass plate, a guide bar bridging 35 said opening on one side of said pane, said shutter being held against said pane by said guide bar, said pane having a guide opening therethrough above said ventilating opening, a cord secured at one end to the upper 40 end of said shutter and extending through said guide opening to be manipulated on the other side of said pane to raise and lower said shutter, said guide bar having a guide slot, and an extension on said shutter 45 engaging in said slot to confine said shutter to vertical movement when it is raised and lowered by means of said cord.

2. In ventilating mechanism, the combination of a window pane having a ventilating 50 opening therethrough, a shutter for said opening in the form of a glass plate, a guide bar extending vertically and bridging said 55 ventilating opening, said bar being secured at its upper and lower ends to said pane, said bar having a vertical guide slot, a pin 60 extending from said shutter through said

guide slot, a cord connected at one end with said pin, a thimble extending through said pane above said ventilating opening and in register with the upper end of said guide slot, said cord extending through said thimble to the opposite side of said window pane to be manipulated to cause raising and lowering of said shutter with reference to said ventilating opening, said bar holding 65 said shutter against said window pane and said pin and slot connection confining said shutter to vertical movement when it is raised and lowered by means of said cord.

3. In ventilating mechanism, the combination of a window pane having a ventilating opening, a shutter for said opening in the form of a glass plate, a vertical guide bar bridging said ventilating opening and said shutter and detachably secured at its 70 upper and lower ends to said window pane, said guide bar having a vertical guide slot, a pin extending from the upper end of said shutter through said guide slot, a guide thimble through said window pane above 75 said ventilating opening and in register with the upper end of said guide slot, a cord, and means for securing said cord at one end to said pin outside of said guide bar, said cord extending through said guide slot and 80 through said thimble to the opposite side of said window pane to be manipulated to raise and lower said shutter with reference to 85 said ventilating opening.

4. In ventilating mechanism, the combination of a window pane having a ventilating opening, a shutter for said opening in the form of a glass plate, a vertical guide bar bridging said opening and shutter and secured at its upper and lower ends to said 90 window pane, said guide bar having a vertical slot, a thimble extending through said window pane above said ventilating opening and in register with said guide slot, a pin extending from said shutter through said 95 guide slot, a fitting secured to the outer end of said pin, a cord secured at one end to said fitting and extending through said guide slot and thimble to the opposite side of said window pane to be manipulated to 100 raise and lower said shutter with reference to said ventilating opening, said guide bar holding said shutter against said window pane and said pin and slot cooperating to confine said shutter to vertical movement, an 105 abutment at the lower end of said bar for said shutter, and a screen secured across said ventilating opening at the side opposite to said shutter.

In witness whereof, I hereunto subscribe my name this 12th day of April, A. D., 1928.

FRANK CALABRESE.
